UNITED STATES PATENT OFFICE.

EMIL STAEBELIN, OF CHICAGO, ILLINOIS.

WRENCH.

Application filed April 6, 1920. Serial No. 371,685.

To all whom it may concern:

Be it known that I, EMIL STAEBELIN, a citizen of the United States, residing at Chicago, in the county of Cook and State of Illinois, have invented certain new and useful Improvements in Wrenches, of which the following is a specification.

This invention relates to wrenches, and has for an object the production of a wrench which may be opened by merely pulling against a fixed object by one of the jaws, and which can be closed by pushing with either jaw. A further object is to provide a wrench which is automatically opened when not in use, so that it can conveniently be applied to a nut; so that, by picking up the wrench with one hand, it may be applied to the nut and closed to fit the nut, by pushing against the nut, and then may be operated as much as may be desired. When the nut has been turned as far as is convenient, by merely relieving the wrench of its pressure against the nut, it will be opened, and it then can be rotated backwardly for a new grip on the nut, and then closed as before; this process being repeated somewhat the same as is the practice with ordinary forms of pipe wrenches. A further object of the invention is to provide locking means, so that, when desired, the wrench jaws may be locked snugly against the nut so that the nut may be turned without any possibility of the jaws of the wrench being forced apart; and the jaws may be locked in any position desired with reference to the nut, so that the wrench may be easily removed and turned to a new position, as is the case with any ordinary type of wrench which is adapted to fit the particular nut. Other objects of the invention will be apparent from a consideration of the accompanying drawings and the following description thereof.

Of the accompanying drawings Fig. 1 is a side view of a wrench which embodies the features of my invention; Fig. 2 is a similar view of the wrench rotated 90° from Fig. 1; and Fig. 3 is a section along the line 3—3 of Fig. 2.

The wrench which I have provided, consists of a casing 5, which forms the handle. In this casing is slidably mounted a shank 6, upon the outer end of which is fixed the head jaw 7 of the wrench; and another shank 8 is slidably mounted in the casing adjacent the shank 6; and to this shank 8 is fixed the other jaw 9. A toothed rack 10 is

formed on the shank 6, and a toothed rack 11 is formed on the shank 8. Pivoted to the casing in any suitable manner, as by a pin 12, is a pair of pinions 13 and 14, each of the pinions being fixed to the pin 12. The pinion 13 meshes with the rack 10 and the pinion 14 meshes with the rack 11.

By this structure it will be seen that, if the casing 5 is held stationary and the jaw 7 is pressed inwardly the pinions 13 and 14 will be rotated by the rack 10, and the pinion 14 which meshes with the rack 11, will force the rack, and hence the jaw 9, inwardly; so that both jaws will be forced inwardly with reference to the casing 5. But, as the pinion 13 is larger than the pinion 14, the jaw 7 will move inwardly proportionately faster than the jaw 9, and the two jaws will close, as they move inwardly. The ratio of the diameters of the pinions may be made any suitable amount. I prefer for the purpose to have this ratio two to one. It will also be seen that, by holding the casing 5 and pressing either of the jaws inwardly, the two jaws may be closed towards each other as may be desired; or, conversely, by pulling outwardly on either of the jaws, the two jaws may be forced apart as much as may be desired. Hence, if it is desired to operate the wrench with one hand, or for other reasons, by pressing either of the jaws the jaws may be forced together any desired amount. Or if the jaws were not opened sufficiently, by pulling on a fixed object by either jaw the two jaws will be forced apart. A lug 28 provides means for pulling on the outer jaw when the jaws are closed.

However, in order to more conveniently use the wrench with one hand, or otherwise, I have provided means for automatically opening the jaws whenever the wrench is not in use. These means comprise a spring 15 placed between the end of the casing 5 and the shank 8, so that the spring at all times tends to force the shank out of the casing. Hence, when the wrench is released from the nut, or the action of the spring is not in some other manner prevented, the spring will force the shank 8 outwardly, and thus open the jaws to the maximum amount. A stop 16 limits the amount that the jaws can be opened by the stop coming in contact with the end 17 of the shank 6. Hence, by the use of the spring, to operate the wrench it is necessary only to take hold of the handle of the wrench, place the jaw 9 against

the nut and press until the two jaws are brought snugly against the nut.

When used in the manner hereinabove set forth, there is more or less tendency of the jaws to be forced apart. The action of the nut is to tend to separate the jaws; and, while the pushing against the inner jaw tends to hold the jaws together, yet the pushing against the head jaw tends to open the jaws; and the latter is somewhat more effective because the pinion with which the head jaw is associated is larger than the other pinion, and hence the effect of the pressure on the jaw is greater than the effect of the pressure on the other jaw.

While this tendency of the jaws to open when the wrench is in use is frequently immaterial, yet I have provided means for locking the two jaws together when they have been set properly for the particular use. These means comprise a U-shaped member 18 which straddles the casing 5, the pin 12 passing through slots 19 in the member 18. Fixed to the member 18 is a pin 20 having beveled corrugated surfaces 21 on its inner end, these edges being adjacent the beveled corrugated edges 22 of the shanks. When the jaws have been set in the right position, if the pin 20 is forced against the beveled edges 22 of the shanks the pin will bind the shanks in place, so that relative movement thereof will be prevented. In order to press the pin 20 against the shanks with sufficient force I provide a second member 23 which also straddles the casing 5, as well as the arms of the member 18, and the pin 12 passes through openings 24 in the member 23. Fixed to the member 23 is an operating handle 25, and fixed to the member 23 are pins 26 which pass through slots 27 in the member 18, so that when the member 23 is rotated on the pin 12, the pins 26 will be forced inwardly or outwardly carrying with them the member 18; and if the pins 26 are forced outwardly they will force the pin 20, by means of the member 18, against the beveled portion of the shanks, thus binding the shanks in their set position. By means of the handle 25 the operator may conveniently press the pins 26 outwardly, and hold them in such position by the same hand that is used in operating the wrench. A spring 28 is adapted to force the handle 25 away from the casing, so as to release the shanks from the pressure of the pin 20, and allow the jaws to be freely opened or closed; so that if the wrench is released by the hand, and otherwise is free to operate automatically, the handle 25 will be forced outwardly, releasing the shanks, and the spring 15 will force the jaws apart. A link 29 is provided for locking the handle 25 in its inward position, whenever it is desired to do so, so that the handle 25 does not need to be held inwardly

by the hand; and it is to be understood that the jaws, by these locking means may be locked in any position, so that the jaws may be tightly held against the nut, or may be loosely fitted to the nut so the wrench can be removed and turned to a new position with reference to the nut as is the case with any ordinary wrench.

Although I have described with some particularity various details of the construction of my preferred form of wrench, yet it is to be understood that modifications therein may be made by those skilled in the art without departing from the spirit of my invention as disclosed by the following claims.

I claim as my invention:

1. A wrench comprising a handle, two pinions mounted for rotation in said handle, said pinions being non-rotatable relatively to each other, two shanks slidably mounted in said handle, each of said shanks having a gear rack thereon, and each of said shanks projecting out of said handle, said racks meshing with the respective pinions, each of said shanks having a wrench jaw fixed to its outer end, one of said pinions being smaller than the other.

2. A wrench comprising a handle, two shanks slidably mounted in said handle, each of said shanks having one end projecting from said handle, and having a gear rack formed on its other end, a jaw mounted on the outer end of each of said shanks, two pinions non-rotatable relatively to each other, rotatably mounted in said handle and meshing with the respective racks, said pinions being of unlike dimensions.

3. A wrench comprising a casing, two shanks slidably mounted in said casing each with one end projecting from the casing, a jaw fixed to the outer end and a rack fixed to the inner end of each of said shanks, a pair of relatively fixed pinions of unlike diameters rotatably mounted on said casing and meshing with the respective racks, and resilient means tending to force one of said shanks outwardly.

4. A wrench comprising a casing, two shanks slidably mounted in said casing each with one end projecting from the casing, a jaw fixed to the outer end and a rack fixed to the inner end of each of said shanks, a pair of relatively fixed pinions of unlike diameters rotatably mounted on said casing and meshing with the respective racks, and means for preventing relative movement of said shanks.

5. A wrench comprising a casing, two shanks slidably mounted in said casing each with one end projecting from the casing, a jaw fixed to the outer end and a rack fixed to the inner end of each of said shanks, a pair of relatively fixed pinions of unlike diameters rotatably mounted in said casing

and meshing with the respective racks, and means for preventing relative movement of said shanks, said means comprising an arm pivoted to said casing and arranged to prevent said relative movement when said arm is forced towards said casing.

6. A wrench comprising a casing, two shanks slidably mounted in said casing each with one end projecting from the casing, a jaw fixed to the outer end and a rack fixed to the inner end of each of said shanks, a pair of relatively fixed pinions of unlike diameters rotatably mounted in said casing and meshing with the respective racks, means for preventing relative movement of said shanks, said means comprising an arm pivoted to said casing and arranged to prevent said relative movement when said arm is forced towards said casing, and resilient means for forcing said arm away from said casing.

7. A wrench comprising a casing, two shanks slidably mounted in said casing each with one end projecting from the casing, a jaw fixed to the outer end and a rack fixed to the inner end of each of said shanks, a pair of relatively fixed pinions of unlike diameters rotatably mounted in said casing and meshing with the respective racks, means for preventing relative movement of said shanks, said means comprising an arm pivoted to said casing and arranged to prevent said relative movement when said arm is forced towards said casing, resilient means for forcing said arm away from said casing, and means for locking said arm down adjacent said casing.

8. A wrench comprising a handle, two shanks slidably mounted in said handle each with one end projecting from the handle, a jaw fixed to the outer end and a rack fixed to the inner end of each of said shanks, a

pair of relatively fixed pinions of unlike diameters rotatably mounted in said handle and meshing with the respective racks, and means for preventing one of said racks from moving relative to said handle.

9. A wrench comprising a casing, two shanks slidably mounted in said casing each with one end projecting from the casing, a jaw fixed to the outer end and a rack fixed to the inner end of each of said shanks, a pinion rotatably mounted in said casing and operatively connected with the respective racks, and means for preventing longitudinal movement of said shanks.

10. A wrench comprising a handle, two pinions mounted for rotation in said handle, said pinions being non-rotatable relatively to each other, a first and a second shank slidably mounted in said handle, each of said shanks projecting out of said handle and having a wrench jaw fixed to its outer end, said first shank having a rack on its inner end, said rack meshing with one of said pinions, and means operatively connecting the inner end of said second shank with said other pinion.

11. A wrench comprising an elongated casing, a first and a second shank slidably mounted in said casing, one end of each of said shanks projecting from said casing, a jaw fixed to each of said projecting ends, a rack fixed to the inner end of said first shank, a pinion rotatably mounted in said casing and meshing with said rack, said pinion being operatively connected with said second shank, and means for preventing relative movement of said shanks, the axes of said shanks being parallel with the axis of said casing.

In testimony whereof, I hereunto set my hand.

EMIL STAHELIN.
